PUMPING SYSTEM

Armistead Leake, Mobile, Ala., assignor to Lerio
Patent Cup Co., Inc., Mobile, Ala.

Application June 9, 1944, Serial No. 539,435

1 Claim. (Cl. 103—25)

This invention relates to pumps and pumping equipment and it has particular reference to water pumps and especially to a pumping system.

The principal object of the invention is to provide what actually constitutes a pumping system, whose exceptionally simple design and assembly render it highly adaptable for use on farms and in rural districts where municipal water pressures are not available. The small number of working parts in the system and the particular arrangement thereof makes for speedy and convenient assembly and replacement as well as providing, in a reciprocating pump of this character, effective means for reducing leakage to a negligible degree.

Another object of the invention is to adapt the highly advantageous principle of the reciprocating pump to a pumping system capable of convenient attachment to the casing of a common water well and by the simple expedient of connecting the motor of the pump to available electrical source, the system is placed in condition for operation.

Still another object of the invention is to provide automatic means for starting and stopping the motor as pressures in the system vary. Moreover, in event of failure of the automatic means to function properly under maximum pressure, provision is made for automatically effecting disengagement of the driving belt from the main shaft pulley to prevent overloading the motor.

With the foregoing objects as paramount, the invention has further reference to certain features of accomplishment which will become apparent as the description proceeds, taken in connection with the accompanying drawing wherein:

Figure 1 is a perspective view of a pumping system constructed according to the present invention with parts of the tank and bowl cut away.

Figure 2 is a side elevational half view of the tank and bowl, showing the discharge or service outlet.

Figure 3 is a fragmentary view of the pumping assembly in vertical section, and

Figure 4 is a detail view of one of the connecting rod bearings.

Continuing with a more detailed description of the drawing, reference is made primarily to Figure 1 wherein numeral 10 denotes a tank or reservoir, closed at the top and provided at its base with a right angle, annular flange 11. Below the tank 10 is a bowl 12, which, in conjunction with an intermediate plate 13, defines a chamber 14. The bowl 12 has an annular flange 15 about its upper rim, the outer edge of which

is turned upwardly to embrace the perimeter of the tank flange 11 as well as that of the plate 13 which is interposed between the two flanges 11 and 15. Gaskets 16 are disposed between the flange 11 and plate 13 and between the latter and flange 15 and a plurality of bolts 17 serve to hold the assembly securely together.

The bowl 12 converges at its bottom about an intake pipe 18 which is preferably internally threaded to receive the stand pipe or casing of a well, not shown. Water constrained to move upwardly into the tank 10 in a manner to be presently explained, is drawn off through the outlet or service pipe 19 (Fig. 2), which may extend to a point of consumption, but for purposes of illustration, carries a T 20 and a faucet 21.

At diametrically opposite points in the walls of the tank 10, there are provided bushings 22, welded or otherwise firmly secured in place. These bushings contain bronze bushings 22a which serve as bearings for a shaft 23, which latter extends entirely through the tank. The inner diameter of the bushings 22 is greater than that of the shaft 23, to accommodate bronze bushings 22a and to define an annular space in each bushing, to fill which, packing washers 24 are inserted to snugly embrace the shaft and prevent leakage of water from the tank. As a further precaution against leakage, a cap 25 is threaded onto one end of one bushing 22 while the opposite bushing carries a packing gland comprised of a nut 26 containing a gasket 27 which is compressed against the outer end of the bushing by the nut.

Mounted on the shaft 23 is a crank composed of a sleeve 28, held against rotation on the shaft by a set screw 29. Formed on each end of the sleeve 28 is an eccentric 30 and to each eccentric is affixed a hollow crank pin 31. Obviously, the cranks 31 may be formed integrally with the eccentrics and sleeve 28 but it has been found to be more economical and to produce better results to construct the crank in the manner shown. By making the cranks hollow, the assembly is much lighter and less power is utilized in operating the pump. The shaft 23 and sleeve 28 are made of materials immune to rust and corrosion and, although these parts are constantly submerged in water, no ill effects are caused either to the parts or to the water passing through the system.

Embracing the cranks 31 are the straps 32 of connecting rods 33, and interposed between the straps and cranks are bearings 34 (Fig. 4) of rubber but of conventional manufacture, known as "cutless bearings." The connecting rods 33 carry conventional pistons made up of valve cages

35; spring controlled valves 36 and leathers 37, the latter being held in fixed relation to the cages by means of the removable valve seats 38, threadedly entering the bottoms of the cages as shown in Figure 3 particularly.

Pressed into apertures in the plate 13 disposed intermediate the tank 10 and bowl are cups 39 which serve as cylinders and receive the pistons. These cylinders each have intake ports *a* at the bottom, closed by valves 40, the latter being controlled by springs 41, surrounding stems 42 below the cylinders 39. Mounted in the bottom of the bowl 12 is a standing valve 43 (Fig. 1), which controls ports 44 in its seat and prevents liquid from returning to the well once it has been elevated by reciprocating action of the pistons. This valve is gravity controlled.

To reciprocate the pistons, a drive pulley 45 is secured to the extended end of the shaft 23 by means of a collar 46 and set screw 47. It will be particularly noted that this pulley has a flange 48 on the inside only of its rim and carries a driving belt 49. The object of this single flange is to permit the belt 49 to ride off the pulley in event of excessive pressures, causing the shaft to become difficult to turn. Thus, overloading the motor 50 to a degree likely to cause damage thereto is rendered impossible. The belt 49 surrounds a grooved pulley 51 on the armature shaft of the motor, thereby completing the drive to the shaft 23.

The motor 50 is supported on mounting brackets 52 fastened to the back of the tank 10 and, by virtue of slots 53, receiving mounting bolts 54, the motor 50 may be raised and lowered with respect to the tank and by so doing, the belt 49 is tightened or loosened as required.

A supply of water is maintained in the tank 10 at all times to insure adequate pressure for delivery, usually about 40 pounds, although this may vary. To insure such supply, an automatic switch 55 is provided of conventional manufacture. This switch is controlled by a diaphragm (not shown) which is deflected at a predetermined maximum pressure to actuate the switch to open the motor circuit through wires 56. When the minimum pressure prevails in the tank 10, the diaphragm yields to superior spring pressure to close the motor circuit, starting the pump.

It sometimes happens that the pump, becoming water logged, will frequently start and stop with no effect except to impose undue wear on the motor. To overcome such condition, a bleeder port is provided in the tube which leads from the

tank to the switch 55, which port is covered normally by a screw 57 (Fig. 1). The current to the motor 50 is turned off and the faucets are opened. As soon as water ceases to flow through the faucets, the screw 57 is removed to allow additional water to drain from the tank. The screw 57 is replaced and the current turned on, after which the pump is again ready for normal operation.

It is apparent from the foregoing that particularly through and by virtue of the unusual design of the mechanism for imparting motion to the pistons, the cylinders, the mounting plate therefor and the bowl of the tank, there is provided a pump exceptionally light in weight but sturdy in construction. This has its advantages, not only in shipping and installing but likewise represents a considerable saving in material and manufacture and minimizes work of assembling.

Manifestly, the construction as shown and described is capable of some modification and such modification as may be construed to fall within the scope and meaning of the appended claim is also considered to be within the spirit and intent of the invention.

What is claimed is:

In a water pumping system the combination comprising a storage tank having an outlet, a bowl detachably mounted on the lower end of said tank, a plate whose perimeter is interposed between said tank and bowl, constituting a partition therebetween and defining a chamber in said bowl, parallel cylinders depending from said plate, valves in said cylinder, diametrically opposed, tubular bearings affixed in the walls of said tank above said plate, having threaded outer ends, a shaft extending diametrically across and entirely through said tank and through said bearings, packing embracing said shaft within said bearings, packing glands threaded onto the ends of said bearings, hollow eccentrics opposingly affixed to the intermediate portion of said shaft, connecting rods mounted on said eccentrics, pistons having valved passages for the flow of pumped liquid and arranged to be reciprocated by said rods in said cylinders, a pulley on an extended end of said shaft, a motor and belt means for driving said pulley, and a valved inlet in the base of said bowl for admitting water into said bowl under the influence of said pistons, to be elevated thereby into said tank, means for drawing water from said tank and means responsive to variations of pressure in said tank for opening and closing the circuit to said motor.
